corporation of Germany

Filed Apr. 1, 1960, Ser. No. 19,427

Claims priority, application Germany Apr. 2, 1959
7 Claims. (Cl. 233—21)

The present invention relates to safety devices for centrifuges having an outer hood covering the centrifugal drum during normal operation and a flow conduit extending through an opening in the centrifuge drum hood into said drum for passage of flowable material therethrough during operation of the centrifuge, said conduit being releasably secured at the hood opening, and more particularly to a safety device having blocking means normally preventing the release of said conduit secured to said hood, yet which is released by energizing means upon the cessation of rotation of the centrifugal drum.

Conventional high-speed centrifuges, capable of attaining a high number of revolutions per unit of time, are usually provided with a hood or cover member which is either mounted on the centrifuge surrounding frame or is hingedly attached thereto, said hood cover serving to enclose the upper portion of the centrifugal drum or serving to seal an opening in the upper portion of the centrifugal drum surrounding outer casing. In the case of centrifuges having free liquid outlets, such covers or hoods are often subdivided by means of intermediate partitions into axially disposed adjacent collecting chambers for the separated components obtained during centrifugal operations. Where flowable materials, such as liquids, are centrifugally processed, the separated fractions are urged during centrifuging into such different chambers through the gap existing between the drum and the separating partition.

It is well understood that before a centrifuge may be taken apart for the purpose of cleaning, the outflow of materials from the drum must be terminated, and the drum itself brought to a standstill. Unfortunately much time is wasted during the period between the cut-off of the feed material to the drum and the point where the drum itself has come to rest. Generally, in the case of centrifuges of the aforementioned type, after the stopping of the centrifuge feed material, the draining of the drum, the disconnecting or shutting off of the drive motor, and the switching on of the brake to bring the centrifugal drum to a standstill, the hood or cover may be forthwith opened for access thereto without danger to the service personnel.

With respect to newer centrifuge constructions, particularly those in which the separated phases are drawn off by means of small axially arranged peeling discs or cups, the feed and outlet conduits are all, or at least in part, fastened to the hood or cover and extend downwardly therethrough into the drum. Consequently, the hood or cover may only be opened after disconnecting these conduits within the drum from their points of connection to and through the cover.

In making these conduit connections, the little peeling discs, which are axially provided on a shaft, are connected via the shaft or a conductor element to the hood so that they are positioned co-axially to the axis of the drum whereby said discs stand free from the corresponding disc chambers positioned in the rotatable drum, and the openings of the disc channels or conduits are disposed in the conductor element at the particular height of the annular collecting chambers.

In disconnecting the feed and discharge conduits, passing through the hood or cover of the drum, as aforesaid, the revolving drum must be brought to a standstill first or else the discs, which will also become disconnected with the disconnecting of said feed and discharge conduits,

2

will fall into the rotating drum and be damaged by the moving parts. Besides the possibility of considerable damage to the various drum parts, the servicing operator is placed in danger due to the possible deflection of broken parts from the open drum.

While a tachometer may be attached to the centrifuge to indicate the number of revolutions of the drum axle, such devices and indicators are not accurate at low speeds. This may be explained by the fact that for the purpose of attaining increased precision of readings of the number of revolutions at high speeds the zero point, i.e. the point indicating that the centrifuge has come to a standstill, must be suppressed. As a result, even with the known indicators, the exact point where the centrifuge has come to a standstill may not be actually perceived by the operator without opening the drum hood or cover.

It is an object of the present invention to overcome the foregoing drawbacks and to provide a safety device for centrifugal drums, having means for blocking the release of the flow conduit secured to the cover or hood of the centrifugal drum at the opening therein while the drum is being rotated and energizing means actuatable upon the stopping of the drum rotation for releasing said blocking means.

Other and further objects of the invention will become apparent from a study of the within specification and drawings in which:

FIGURE 1 is a diagrammatic side view partially in section of a centrifugal drum hood or cover having inlet and outlet conduits attached thereto, illustrating the safety device in accordance with one embodiment of the invention;

FIGURE 2 is a diagrammatic side view of the centrifugal drum hood of FIGURE 1 illustrating the manner of conduit attachment;

FIGURE 3 is a top view of the embodiment shown in FIGURE 1;

FIGURES 4 and 4a are diagrammatic enlarged side views, partially in section, of two embodiments of a safety device in accordance with the invention, and

FIGURE 5 is a diagrammatic view of a circuit for operating the safety device of the invention.

In accordance with the invention, it has been found that the aforementioned disadvantages may be overcome by providing a safety device for a centrifugal drum having an outer hood covering the drum during normal operation and at least one flow conduit extending through an opening in the hood into the drum for passage of flowable material therethrough, wherein said conduit is releasably secured to said hood at said opening during normal operation. This safety device comprises blocking means normally preventing the opening of the drum cover otherwise caused for example by releasing the inlet and outlet conduits and energizing means actuatable upon the cessation of rotation of the drum for releasing the blocking means. In this connection, the blocking means may specifically prevent the disengagement of the feed and outflow conduits passing through the hood or cover and prevent the opening of the hood or cover itself until the drum has reached a position of rest. At this point energizing means are actuated which release the blocking means and allow the disconnection of said conduits and the opening of the drum cover. Consequently, in accordance with the invention, a premature disconnecting of the feed and discharge lines or a premature opening of the drum cover closure elements is no longer possible, and the aforementioned danger, heretofore present, is completely eliminated.

An essential feature of the invention concerns the energizing means for automatically releasing the blocking means upon the drum's coming to a standstill. In this regard a suitable generator may be positioned on the

centrifuge drive shaft or on a suitable shaft connected for rotation simultaneously with the drive shaft. By means of the rotation of said shaft, the generator produces a convenient voltage, depending on the number of revolutions of said shaft, which is connected, either directly or via various suitable relay circuits, so as to sense the point at which the centrifuge reaches a standstill. The generator may be connected, either as a shut off for the releasing means for the blocking means during the rotation of the drum, which actuates said releasing means upon the drum's reaching a standstill, or said generator may act in a positive manner to keep the blocking means in blocking position during the rotation of the drum, and upon the drum's reaching a standstill, causing the releasing means to operate. However, it will be realized that any current source may be used which directly or indirectly acts in consequence of drum rotation to energize and deenergize the releasing means for the blocking means, in addition to the simple generator means as described.

In accordance with one embodiment of the invention, the blocking means comprises a blocking arm for preventing the disconnection of the feed line and a stopping arm for preventing the disconnection of the discharge line and conductor element passing into the drum. These arms are suitably provided on a rotatable cylinder element appropriately seated on the drum cover. The cylinder is provided with a recess defined in its outer surface which releasably receives the end of a rod positioned for movement back and forth within a chamber adjacent said cylinder and also preferably seated on said drum hood or cover. Said rod is for example spring loaded so that said rod end is normally urged into the cylinder recess. The other end of said rod is slidably received within an electric coil element. Said coil is connected in circuit with the generator on the centrifuge drive shaft or other means used for sensing the cessation of drum rotation so that when the drive shaft ceases to turn and for example said generator, accordingly, ceases to generate voltage, a relay is switched sending current through the coil surrounding said other end of the rod. By reason of such current, said rod is withdrawn from said recess into the coil, permitting the cylinder to turn freely and displace said blocking arm and stopping arm or lever from their blocking positions. The drum connections, through the hood, may now be disengaged with safety.

Alternately, the coil element and the spring-loaded feature may be reversed in operation so that the rod is normally urged out of said recess and upon actuation of said rod in the opposite direction, by energizing said coil, the cylinder and, in turn, the blocking arm and stopping lever are held in safety position.

It will be appreciated that the particular arrangement for engaging said blocking means in place and for releasing said blocking means upon the stoppage of the centrifuge rotation is not critical. Accordingly, since the generator is to be operated only during the time the centrifuge is rotating, the generator may be disposed for operation with respect to any shaft so long as that shaft rotates simultaneously with the shaft of the centrifugal drum and ceases to rotate at the same moment as that of the centrifuge shaft. Generally, any circuit means including relays for example may be provided for energizing the coil in response to the rotation or cessation of rotation of the drum either to urge said rod into said recess or withdraw the same therefrom as the case may be.

As a further preferred feature, the blocking means may be provided with a suitable arresting element such as a coil spring normally urging the blocking means into the closed position, i.e. blocking the opening of the hood or cover so that the rod may be replaced again in locking position in said recess. Moreover, the circuit means may be provided so that the current supply to the drum motor

only flows when the blocking means is in blocking position closing the hood or cover.

As a further feature of the invention, the circuit for the energizing means, for automatically releasing the blocking means, may include an additional element capable of emitting an acoustic or optical signal, such as the ringing of a bell or the flashing of a light, at the moment the centrifuge comes to a standstill. Such a signal would indicate the stoppage of rotation of the drum to the service personnel immediately, and thus effect a saving in otherwise wasted time after the centrifuge has stopped and before the workmen open the hood or cover.

Referring to FIGURE 1, a stationary hood 1 is provided spaced from and extending around the moving centrifugal drum so as to enclose the same. Hood 1 is provided with a central aperture 2 through which the conductor 4, equipped with one or more connecting flow lines such as line 3, is introduced into the drum interior. Conductor 4 is retained by means of a tension ring 5, operating with a tension screw 6 (see FIG. 2) solidly on flange rim 7 of the stationary hood 1. The stationary disc shaft 8, containing one or more peeling discs 14 for separating the different phases of the flowable material to be centrifuged, is positioned loosely in the upper portion 25 of the drum before closing the drum hood. In this manner, the upper portion of said disc shaft 8 projects through the conductor 4 and is centered in place by the threaded handle body 9 drawn tightly against its seat in the conductor 4, which is provided with a correspondingly threaded portion for this purpose. The elbow portion 11 of the feed line 12 is fastened tightly to the upper end of handle body 9 by means of handle body 13. For this purpose handle body 13 and handle body 9 are provided with corresponding threaded portions.

Upon the termination of a centrifuging operation, after the closing off of the feed line 12 and outlet line 3, elbow portion 11 may be detached by unscrewing handle body 13 and removed without danger. On the other hand, the detachment of handle body 9 and of tension screw 6 must await the cessation of rotation of the drum or else disc shaft 8 if prematurely released will be downwardly displaced causing the peeling disc 14 to fall against the rotating drum part 15. Accordingly, the danger of damage to the drum parts and injury to the service personnel may result.

For this purpose, in accordance with the invention, as indicated in FIGS. 2 and 3 a rotatably mounted cylinder 18 is provided on the drum hood, having a blocking arm 16 and a stopping lever 17. In the safety position, the blocking arm 16 is so disposed that its upper end portion abuts a corresponding gripping extension of handle body 9 while the outer portion of stopping lever 17 abuts tension screw 6 preventing the loosening of said screw. As may be seen from FIGURE 3, when the safety device is 55 in blocking position, a premature disconnection of the handle body 9, to which is connected the shaft 8 carrying the little disc 14, as well as a disconnection of conductor 4, is completely prevented. Only upon the stoppage of rotation of the drum, so that the energizing means may 60 automatically actuate the releasing mechanism for the blocking means, will the drum cover be able to be opened.

As shown in FIGURE 4, cylinder 18 is provided with a recess, or bore hole 19 into which a spring-loaded bolt or rod 21 may be received in locking engagement. Rod 65 21, surrounded by loaded spring 20, is positioned for back-and-forth movement within slide cylinder 24, preferably fixedly attached to the drum hood 1. Spring 20 is positioned between retaining disc 22, attached to bolt 21, and the annular counter-bearing 23, fixed to the inside wall of cylinder 24. The distal end of bolt 21, i.e. the end remote from cylinder 18, projects within a wire coil 25, connected in circuit with an energizing means such as a generator (not shown) for actuation upon the cessation of rotation of the drum. Bolt 21 is drawn further within the core of coil 25 against the force of

loaded spring 20, acting at one end against fixed bearing 23 and at the other against disc 22 on bolt 21, when said coil is energized by current passing therethrough. In this way, the locking of cylinder 18, by the end of bolt 21, within recess 19, is released, permitting cylinder 18 to be rotated and blocking arm 16 and stopping lever 17 to be displaced from blocking position.

In order to ensure that the blocking means for hood 1 are always in the blocking position when the drum is running, cylinder 18 is preferably provided in the embodiment shown in FIGURE 4 with a central passage for rotatably mounting the cylinder onto bearing bolt 27 fixedly attached to hood 1. The upper portion of the channel of cylinder 18 is enlarged in order to receive therewithin loaded coil spring 26. Spring 26 is attached at one end to bolt 27 and at the other to cylinder 18 under tension normally urging cylinder 18 and in turn blocking arm 16 and stopping lever 17 into blocking position. In this manner, upon the release of blocking means 16 after an opening of the drum cover 1, the counter-action of spring 26 automatically turns cylinder 18 back to the starting position for blocking engagement, so that recess 19 is again placed in communication with bolt 21. Accordingly, the hood 1 will be safely maintained in closed position when the drum motor is actuated.

Alternately, or besides the loaded spring arrangement in cylinder 18, an extension contact arm may be provided on the end of bolt 21 remote from recess 19 as shown in FIGURE 4a. In this case, contact arm 28 is positioned with respect to safety switch contacts v for closing the overall circuit for the drum motor only when bolt 21 is positioned in recess 19, thus ensuring that the blocking position is maintained before the drum can be rotated. The energizing of the coil 25 for releasing rod 21 from blocking position is suitably effected by generator G positioned for rotation directly or indirectly with the drive shaft of the drum motor as is more clearly seen in FIGURE 5.

Referring to FIGURE 5, the operation of the preferred circuit for actuation of the centrifugal arrangement which shows various contacts in closed position is as follows. Upon closing main switch S, current flows across closed contacts r of relay R when drum is stopped and closed contacts u₁ of the pressure switch U normally held in closed position under spring pressure, and through coil 25 completing the circuit. Bolt 21 is temporarily moved further within coil 25 now energized and out of recess 19 so as to effect release of the bolting position and permit opening of the hood 1. Arm 28 connected to bolt 21 simultaneously moves outwardly thus opening the contacts v.

If pressure switch U is now actuated while switch S remains closed, contacts u₁ are opened causing interruption of current flow to coil 25. Moreover, if recess 19 is again aligned with the bolt 21, due to the action of spring 20, bolt 21 moves back into locking engagement with recess 19. Since contacts v are only closed when bolt 21 is in locking position, upon such actuation of pressure switch U, but only when the locking position is again maintained, current passes via closed switch S, contacts v and contacts u₂ to actuate relay W which thus automatically closes main switch X to start electric motor M, the driving source for rotation of drum D via transmission shaft E. Simultaneously, relay W closes self-holding contacts w, so that relay W remains actuated and in turn switch X remains closed even after the release of pressure switch U. Current to relay W is now provided in this connection via normally closed contacts y of pressure switch Y and the self-holding contacts w.

Upon switching on of motor M, generator G positioned on any desired axle of the drive transmission means, produces a predetermined voltage sufficient to actuate a shift of relay R and in turn to cause the opening of contacts r. Coil 25 accordingly remains deenergized upon release of pressure switch U even though contacts u₁ are

again closed, since contacts r remain open due to the shift of relay R caused by generator G.

In order to shut off motor M, pressure switch Y need merely be pressed. This interrupts current flow to relay W which shifts to cause the openings of switch X. Simultaneously, current to self-holding contacts w is also interrupted.

As long as drum D is running, even after the switching off of motor M, generator G still produces voltage sufficient to actuate relay R to maintain contacts r in open position. Only upon the cessation of drum rotation does the generator voltage decline, and in turn the flow of current to relay R, whereby contacts r are again closed and current caused to flow through coil 25. Now, bolt 21 is drawn further within coil 25 and out of recess 19, releasing cylinder 18 for opening the drum hood. Blocking arm 16 and stopping lever 17 may accordingly be rotated out of blocking position together with cylinder 18 so as to permit release of handle 9 and screw 6.

Coil 25 may be suitably deenergized during prolonged interruptions in centrifugal operation by merely turning off switch S.

As aforesaid, the energizing current for coil 25 is switched on by suitable circuit means upon the stoppage of rotation of the drum as sensed by the suitably situated generator or other means with respect to the drive shaft of the centrifuge or other suitable shaft element rotating simultaneously with the drum and ceasing to rotate at the same moment as said drum ceases to rotate. The voltage produced by the generator during rotation of the drum may be conveniently utilized for activating a relay, which, upon reaching a specific voltage value, for instance, a voltage value of zero (when the drum reaches a standstill) switches on, via closed circuit contacts, another current which may pass to coil 25. The switch for this other current source may be appropriately coupled with the main switch for turning on and off the centrifuge drive so that, upon switching off the centrifuge, the current to the relay is switched on and ready to energize the coil upon the generator's reaching a zero voltage value.

It will be appreciated that, while the foregoing specification and accompanying drawings have been set forth for the purpose of illustration, it will be obvious to those skilled in the art that various modifications and changes may be made without departing from the spirit and scope of the invention, which is to be limited only by the scope of the appended claims.

What is claimed is:

1. Safety device-equipped centrifugal drum arrangement comprising a centrifugal drum, an outer hood covering the drum during normal operation, means defining an opening in said hood, one flow conduit extending into said drum for passage of flowable material therethrough, means releasably securing said conduit to said hood at the opening means, blocking means operatively positioned at said means releasably securing said conduit for preventing during rotation of the drum the release by the releasable securing means of said conduit so secured to said hood, means responsive to the rate of rotation of the drum operatively connected with respect to the drum, and energizing means operatively connected with the responsive means and with said blocking means, said energizing means being actuatable by said responsive means for releasing said blocking means only upon the complete cessation of rotation of the drum.

2. Arrangement according to claim 1 wherein said means releasably securing said conduit to said hood includes a closure element for closing said opening and fastening means for fastening said closure element closed, said conduit being secured to said hood via said closure element, and said blocking means including a displaceable blocking arm for blocking the release of said fastening means and releasable locking means for securing said

blocking arm against displacement, said locking means being released upon actuation of said energizing means to allow displacement of said blocking arm.

3. Arrangement according to claim 2 wherein said blocking arm is mounted on a rotatable base, said base being normally urged under spring force to maintain said blocking arm in blocking position, said base having a recess therein, said locking means including a rod movable into and out of said recess for locking said base against rotation and in turn said blocking arm in blocking position against displacement, spring means being provided for spring urging said rod into said recess, and coil means being provided, energizable by said energizable means, for electrically urging said rod out of said recess.

4. Arrangement according to claim 3 wherein said responsive means includes a first circuit having energizable relay means and generator means therein, said generator means being operatively connected with the drum for generating current in said first circuit for energizing said relay means as long as said drum rotates, and said energizing means includes an energized second circuit having current interrupting switch means and said coil means therein, said relay means being operatively coupled with said switch means for opening said switch means to interrupt current in said second circuit when said relay means is energized during drum rotation and for closing said switch means to permit current to flow in said second circuit to energize said coil means upon complete cessation of drum rotation.

5. In a safety device-equipped centrifugal drum arrangement including a centrifugal drum, an outer hood covering the drum during normal operation, said hood having means defining an opening therein, a closure element closing the opening, releasable fastening means, said closure element being secured to said hood at said opening by said releasable fastening means, and at least one conduit for flowable material extending through said closure element and into said drum, the improvement which comprises blocking means operatively positioned at said fastening means for preventing during drum rotation the release of said fastening means, means responsive to the rate of rotation of the drum operatively connected with respect to the drum, and energizing means operatively connected with the responsive means and with said blocking means, said energizing means being actuatable by said responsive means for releasing said blocking

means only upon the complete cessation of rotation of the drum.

6. Improvement according to claim 5 wherein said blocking means includes a displaceable blocking arm for blocking the release of said fastening means and releasable locking means for securing said blocking arm against displacement, said locking means being released upon actuation of said energizing means to allow displacement of said blocking arm.
- 5 7. In a safety device-equipped centrifugal drum arrangement including a centrifugal drum, an outer hood covering the drum during normal operation, said hood having an opening defined therein, a closure element closing said opening, first releasable fastening means, said closure element being secured to said hood at said opening by said first releasable fastening means, a conductor means extending through said closure element and having a portion insertable into said drum, an inlet conduit defined within said conductor means, a peeling disc defined on the exterior of said conductor means along said insertable portion, a peeling conduit extending through said closure element and provided in flow communication with said peeling disc, a feed conduit, and second releasable fastening means, said feed conduit being releasably secured by said second releasable fastening means to said inlet conduit, the improvement which comprises blocking means including a displaceable stopping arm and a displaceable blocking arm operatively positioned for preventing the release of said first releasable fastening means 20 and said second releasable fastening means, respectively, during rotation of the drum, releasable locking means operatively positioned at said arms for securing said arms against displacement, means responsive to the rate of rotation of the drum operatively connected with respect to the drum, energizing means operatively connected with the responsive means and with said locking means, said energizing means being actuatable by said responsive means only upon complete cessation of rotation of the drum for releasing said locking means to allow displacement of 25 40 said blocking and stopping arms.
